UNITED STATES PATENT OFFICE.

LOTHAR W. FABER, OF NEW YORK, N. Y., ASSIGNOR TO EBERHARD FABER PENCIL COMPANY, A CORPORATION OF NEW YORK.

CARD FOR PENCILS AND THE LIKE.

Application filed August 4, 1921. Serial No. 489,745.

To all whom it may concern:

Be it known that I, LOTHAR W. FABER, a citizen of the United States, and a resident of New York city, in the county of New York and State of New York, have invented new and useful Improvements in Cards for Pencils and the like, of which the following is a specification.

The objects of this invention are to provide an improved card for holding pencils, penholders and similar articles, for purposes of displaying, assembling, packing, storing, shipping or the like, so that a given number of pencils, such as a dozen, can be retained in proper and orderly relation to each other and to other similar units; to obtain a simple and inexpensive construction which shall be efficient and of a neat and pleasing appearance; to enable the empty cards to be collapsed into small space and thus conveniently stored and shipped; to secure a card which shall display both ends of the pencil and engage the same only intermediate its ends; to provide a firm and secure engagement of the pencils by the card and one which increases under the weight of several cards packed together and which tends to relax again when the cards are separated and handled singly; to secure such a holding strip composed of a single piece of material and which needs to be attached to the card only by one edge; to secure such a strip which presents a broad and stable front surface for engagement by other cards in packing, and to obtain other advantages and results as may be brought out by the following description.

Referring to the accompanying drawings, in which like numerals of reference indicate the same parts throughout the several views,

Figure 1 is a front view of a card of my improved construction with a dozen pencils mounted thereon;

Figure 2 is a vertical central section of the middle portion of the same;

Figure 3 is a similar section showing a second card superposed upon the first, as in packing, and

Figure 4 is a detail section taken centrally and longitudinally of the holding strip, and looking upward in Figure 1.

In said drawings, 1 indicates the body portion of my improved card, which is preferably a sheet of cardboard although it might be made of any other suitable material.

This card may be either a display card, with any known means for holding it upright, as illustrated in the drawing by the hole 2 for hanging it up, or it may be solely for packing purposes, or it may be for both packing and display purposes as I have shown it to be.

This body portion 1 is provided with a holding strip 3, which is shown as extending transversely of the body portion about midway between its top and bottom, although the holding strip can be placed on the body portion in any position desired. This holding strip comprises a piece of sheet material, such as cardboard, which can be scored and bent to form angles which are not rigid but will yield more or less with a hinge-action. Any suitable material can be used, but I have found that thin tough cardboard answers the purpose very well. A rectangular piece of such cardboard is taken, of a length desired to extend across the body portion 1 of the card, and this is bent backward along lines 4, 5 at opposite sides of its median longitudinal line so as to leave a front 6 of the desired breadth. Portions 7, 7 of the material which has been bent backward are left in diverging relation, as shown, of a width sufficient to contain longitudinal series of openings 8 arranged in pairs of opposite and aligned openings one in each inclined portion 7, and each pair adapted to receive a pencil 9 or similar article. The material is further bent forwardly and outwardly apart along lines 10, 11 substantially parallel to the lines 4, 5 and correspondingly spaced from the rows of openings 8, so as to form flanges 12, 12 which are adapted to lie in substantially the same plane, substantially parallel to the plane of the front 6, and seat flatwise upon the body portion 1 of the card, as clearly shown in the drawings. One of these base flanges, of course the upper one where the card is to be hung or other supported in upright position, is secured to the body 1 of the card, as by eyelets 13, and the slant sides 7, 7 are preferably of such width that pencils 9 carried by them are spaced both from the face of the body 1 of the card carrying them and from the body 1 of a superposed card lying upon the front 6 as it does in packing.

It will be understood that under the weight of a superposed card or cards of

5 pencils, upon the front 6, the free base flange 12 slips somewhat and the slant sides 7, 7 tend to diverge more, causing them to grip more tightly the pencils 9 in their 10 openings 8. Thus when packed, and during 15 shipment, the pencils are held very firmly against escape or displacement, and yet when they are unpacked and the cards separated individual pencils can be removed with 20 ease and facility. Obviously to some extent, the weight of the pencils in a card tends to spread the slant sides 7, 7 of the holding strip and so cause the pencils to be gripped in their openings 8, particularly if the card 25 is hung up or supported in upright or nearly upright position, and this action aids in retaining the pencils.

20 As a matter of practice according as I make my holding strips 3 more flexible or less flexible, their gripping action upon the pencils is more or less, and thus I can combine as desired the holding power of such gripping with the plain frictional engagement of the pencils in their holes. It will 25 also be observed that pulling upon a pencil to withdraw it at the attached edge of the holding strip tends to cause the slant sides 7, 7 to approach and release the pencil. Obviously, at all times the grip upon a pencil 30 can be relaxed by pressing the slant sides together with one's fingers.

35 Various modifications and changes can be made in adapting my improved card to different articles, without departing from the spirit or scope of the invention, and therefore I do not desire to be understood as limiting myself except as required by the following claims when construed in the light of the prior art.

40 Having thus described the invention, what I claim is:

1. A card for pencils and the like, comprising a body portion and a holding strip secured at one edge to said body portion 45 and free at the other edge to slide on said body portion, said holding strip having in-

clined sides projecting from the body portion, both apertured to receive a pencil or the like and being yielding toward and away from each other. 50

2. A card for pencils and the like, comprising a body portion and a holding strip having at one edge a flange secured flatwise to said body portion and being free at the other edge to slide on said body portion, 55 said holding strip having inclined sides projecting from the body portion, both apertured to receive a pencil or the like and being yielding toward and away from each other. 60

3. A card for pencils and the like, comprising a body portion and a holding strip having opposite base flanges seated flatwise on said body portion, one of them secured thereto and the other free to slide thereon, 65 said holding strip having inclined sides projecting from the body portion and apertured to receive a pencil or the like and said inclined sides being yielding toward and away from each other. 70

4. A card for pencils and the like, comprising a body portion and a holding strip secured at one edge to said body portion and free at the other edge to slide on said body portion, said holding strip having inclined sides projecting from the body portions and a front spacing said sides at a distance from said body portion, said inclined sides being yielding toward and away from each other and apertured to receive a 80 pencil or the like. 75

5. A card for pencils and the like, comprising a body portion and a holding strip secured at one edge to said body portion and having at its other edge a flange free to slide flatwise on said body portion, said holding strip having inclined sides projecting from the body portion both apertured to receive a pencil or the like and being yielding toward and away from each other. 85 90

LOTHAR W. FABER.
